UNITED STATES PATENT OFFICE.

ROBERT W. HOPE AND SAMUEL F. STAMBAUGH, OF SHELBY, OHIO.

WRENCH.

No. 891,257.

Specification of Letters Patent. Patented June 23, 1908.

Application filed September 11, 1907. Serial No. 392,294.

To all whom it may concern:

Be it known that we, ROBERT W. HOPE and SAMUEL F. STAMBAUGH, citizens of the United States, and residents of Shelby, in the 5 county of Richland and State of Ohio, have invented certain new and useful Improvements in Wrenches, of which the following is a specification.

This invention is an improvement in 10 wrenches, which may be used for either pipe wrenches or nut wrenches, as desired; and the invention consists in certain novel constructions and combinations of parts as will be hereinafter described and claimed.

15 In the drawing Figure 1 is a side view of a wrench embodying the invention. Fig. 2 is an edge view thereof. Fig. 3 is a detail view of the side plates showing the jaw block carried thereby and having what for convenience of reference we term the fixed jaw. Fig. 4 is a detail view showing the sliding jaw including the jaw block and the sliding plates carrying the said block, and Fig. 5 is a detail sectional view drawn alongside the handle 25 and showing the rollers and the cam slot receiving the roller on the sliding jaw.

As shown, the fixed jaw comprises the side plates A which are alike, except that they are rights and lefts and are provided with a 30 main plate A' having an opening A² for the pivot B, which connects them with the handle C, and the main plate A' is also provided with slots A³ extending laterally and arranged to receive the projecting ends of a 35 bearing pin D' for the roller D operating in the cam slot C' of the handle C.

The side plates A are provided at their upper edges at one end with projecting lugs A⁴ between which is held the jaw block E of 40 the fixed jaw. The upper edges of the main plate A' are provided with laterally offset portions A⁵ which provide flanges operating as tracks upon which the sliding plates carrying the sliding jaw block move in the operation of the invention. These sliding plates 45 F are formed with main plates F' which are perforated at F² for the passage of the bearing pin D', and these main plates F' are flanged at their upper edges at F⁵ to rest and slide upon the flanges A⁵ of the side plates A, and lugs F⁴ project outwardly from the upper edges of the main plate F' and receive between them the sliding jaw block E' which is secured by suitable fastenings F³ which may 55 be in the form of bolts, as shown.

By preference the handle C is pivoted at

C² to the side plates A at A² and an antifriction roller C³ may surround the pivot pin C² to relieve friction as will be understood from the drawing.

60

It will be noticed that we provide a wrench in which the side plates A and the sliding plates F carry their respective jaw blocks and are flanged to slide one upon the other in the operation of the invention. This flanging of the side and sliding plates also gives such parts rigidity in a lateral direction and aids in securing the desired strength without unnecessarily increasing the weight of the wrench.

65

It will be noticed that the bearing pin D' 70 carrying the roller D operating in the cam slot C' projects into the slots A³ of the side plates so the latter operate as guides in the sliding movement of the sliding jaw as the wrench is operated.

75

The construction is simple, easily constructed and will be found efficient for the purpose for which it is designed.

Manifestly the jaw blocks may be made in any suitable shape and may be toothed, 80 roughed or smoothed as desired and the working faces thereof can be shaped to adapt them to any kind of work.

It will be understood that in operation the jaw blocks and other movable parts of the 85 wrench may be secured by bolts, screws, pins, rivets or other suitable forms of fastening.

In the operation of the invention centrifugal action may be utilized in swinging the handle to open the jaws. Manifestly, jaw 90 blocks of different shapes may be made for various sizes of wrenches.

We claim:

1. The improvement in wrenches herein described, comprising the handle having the 95 pivot opening and the slotted opening beyond the same, a fixed jaw having side plates provided with a main plate having a pivot opening and provided above the same with transversely extending slots and having its 100 upper edge flanged laterally outward and provided at one end with projecting lugs, a fixed jaw block held between the lugs of the side plates, lateral flanges at the upper edges of the main plate forming ways or tracks for the sliding jaw, the sliding jaw having sliding plates comprising the main plates flanged outwardly at their upper edges and having said flanges sliding on the edge flanges of the side plates and provided at one end with outwardly projecting lugs and with the sliding 105 jaw block held between the same, the main 110

- plates of the sliding jaw being provided with openings for the passage of a pivot pin, a pivot pin passing through said openings and through the slotted opening in the handle and projecting at its ends into the lateral slots of the side plates of the fixed jaw, and a roller on the said pin and operating in the slotted opening of the handle, all substantially as and for the purpose set forth.
10. 2. The combination in a wrench, of a fixed jaw block, a sliding jaw block, side plates having lugs carrying the fixed jaw block and also having main plates and outwardly turned flanges at the upper edges of said main plates, a sliding jaw having a jaw block and sliding plates provided with lugs carrying the jaw block, the said sliding plates also having main plates whose upper edges are turned outward forming flanges
- sliding on the flanges of the said plates, and intermediate devices between the fixed jaw and the sliding jaw whereby to operate the latter, substantially as set forth.
3. A wrench comprising a fixed jaw having side plates and lugs projecting therefrom, and a jaw block held between the said projecting lugs, and a sliding jaw having a main plate sliding between the main plates of the fixed jaw and provided with spaced apart lugs and with a jaw block held between the same, and intermediate devices between the fixed and sliding jaw for operating the latter, substantially as set forth.

ROBERT W. HOPE.

SAMUEL F. STAMBAUGH.
